CLAIM

The ornamental design for a disposable stylet, as shown and described.

DESCRIPTION

FIG. 1 is a front end view of a first embodiment of a disposable stylet showing my new design. FIG. 2 is a left side view of the disposable stylet of FIG. 1. FIG. 3 is a top view of the disposable stylet of FIG. 1. FIG. 4 is a right side view of the disposable stylet of FIG. 1. FIG. 5 is a bottom view of the disposable stylet of FIG. 1. FIG. 6 is a rear end view of the disposable stylet of FIG. 1. FIG. 7 is a bottom perspective view of the disposable stylet of FIG. 1. FIG. 8 is a top perspective view of the disposable stylet of FIG. 1. FIG. 9 is a front end view of a second embodiment of a disposable stylet. FIG. 10 is a left side view of the disposable stylet of FIG. 9. FIG. 11 is a top view of the disposable stylet of FIG. 9. FIG. 12 is a right view of the disposable stylet of FIG. 9. FIG. 13 is a bottom view of the disposable stylet of FIG. 9. FIG. 14 is a rear end view of the disposable stylet of FIG. 9. FIG. 15 is a bottom perspective view of the disposable stylet of FIG. 9. FIG. 16 is a top perspective view of the disposable stylet of FIG. 9. FIG. 17 is a front end view of a third embodiment of a disposable stylet. FIG. 18 is a left view of the disposable stylet of FIG. 17. FIG. 19 is a top view of the disposable stylet of FIG. 17. FIG. 20 is a right view of the disposable stylet of FIG. 17. FIG. 21 is a bottom view of the disposable stylet of FIG. 17. FIG. 22 is a rear end view of the disposable stylet of FIG. 17. FIG. 23 is a bottom perspective view of the disposable stylet of FIG. 17. FIG. 24 is a top perspective view of the disposable stylet of FIG. 17. FIG. 25 is a front end view of a fourth embodiment of a disposable stylet.

FIG. 26 is a left view of the disposable stylet of FIG. 25. FIG. 27 is a top view of the disposable stylet of FIG. 25. FIG. 28 is a right view of the disposable stylet of FIG. 25. FIG. 29 is a bottom view of the disposable stylet of FIG. 25. FIG. 30 is a rear end view of the disposable stylet of FIG. 25. FIG. 31 is a bottom perspective view of the disposable stylet of FIG. 25. FIG. 32 is a top perspective view of the disposable stylet of FIG. 25. FIG. 33 is a front end view of a fifth embodiment of a disposable stylet. FIG. 34 is a left view of the disposable stylet of FIG. 33. FIG. 35 is a top view of the disposable stylet of FIG. 33. FIG. 36 is a right view of the disposable stylet of FIG. 33. FIG. 37 is a bottom view of the disposable stylet of FIG. 33. FIG. 38 is a rear end view of the disposable stylet of FIG. 33. FIG. 39 is a bottom perspective view of the disposable stylet of FIG. 33. FIG. 40 is a top perspective view of the disposable stylet of FIG. 33. FIG. 41 is a front end view of a sixth embodiment of a disposable stylet. FIG. 42 is a left view of the disposable stylet of FIG. 41. FIG. 43 is a top view of the disposable stylet of FIG. 41. FIG. 44 is a right view of the disposable stylet of FIG. 41. FIG. 45 is a bottom view of the disposable stylet of FIG. 41. FIG. 46 is a rear end view of the disposable stylet of FIG. 41. FIG. 47 is a bottom perspective view of the disposable stylet of FIG. 41; and, FIG. 48 is a top perspective view of the disposable stylet of FIG. 41. The broken line showing of portions of the disposable stylet of FIGS. 1-48 is included for the purpose of illustrating environmental structure and forms no part of the claimed design.
